[57] CLAIM

The ornamental design for a phonograph cartridge box, substantially as shown and described.

DESCRIPTION

FIG. 1 is a front perspective view of a phonograph cartridge box showing our new design;

FIG. 2 is a top view thereof;

FIG. 3 is a front view thereof;

FIG. 4 is a side view thereof, the opposite side view being identical;

FIG. 5 is a rear view thereof; and

FIG. 6 is an exploded view thereof showing the upper lid displaced from the bottom of the box.
